TIMING DEVICE

Filed Feb. 26, 1948

UNITED STATES PATENT OFFICE

2,574,314

TIMING DEVICE

Thomas R. Arden, Danbury, Conn., assignor to
 Bard-Parker Company, Inc., Danbury, Conn., a
 corporation of New York

Application February 26, 1948, Serial No. 11,200

6 Claims. (Cl. 137—139)

1

This invention relates to timing devices, and has particular reference to a timing device which is especially intended and designed to automatically stop the operation of model airplane engines to predetermine and limit the time periods during which the airplanes are powered in their flights. The present timer may, however, readily be adapted to perform other timing purposes.

One reason for limiting the duration of powered flights of model airplanes is to avoid flying of the same long distances from their launching points and thereby becoming lost. More importantly, however, in model airplane contests, flights for records and the like, the airplanes usually are flown against time rather than against one another, and a basic factor in determining and comparing their performances is the time during which they are powered in flight. It is important, therefore, to provide a timing device by means of which the time during which model airplanes are powered in their flights may be predetermined very accurately.

Accordingly, one special and important object of the present invention is to provide a timing device which is thoroughly reliable in operation to predetermine accurately the length of time during which a model airplane is powered in its flight.

Another special and important object of the invention is to provide a timing device which may readily and easily be adjusted to vary the amount of time during which it operates to perform its function, thereby to variably predetermine the time periods of events which it controls, as, for example, the time period during which a model airplane is powered in its flight.

Another special and important object of the invention is to provide a timing device which completes its operation with a quick action, whereby it is rendered very accurate in the performance of its timing purpose.

In model airplanes, conservation of space and reduction in weight are important considerations. Accordingly, another object of the invention is to provide a timing device which may be quite small in size and of very light weight.

The present timing device is designed to stop an engine by cutting off its fuel supply, and in this connection another object of the invention is to provide a timing device which is designed to accomplish this purpose reliably and positively.

The present timing device is, moreover, of the cylinder and piston, hydraulic type, and in this connection another object of the invention

2

is to provide a timing device of this type which utilizes as its liquid the fuel which it controls.

With the foregoing and other objects in view, which will become more fully apparent as the nature of the invention is better understood, the same consists of a timing device embodying the novel features of construction, combination, and arrangements of parts, as are illustrated by way of example in the accompanying drawings and as will be hereinafter more fully described and claimed.

In the accompanying drawings, wherein like characters of reference denote corresponding parts in the different views:

15 Figure 1 is a central, longitudinal section through a timing device constructed in accordance with the invention.

Figure 2 is an end view of the device; and
 Figure 3 is a cross section on the line 3—3 of
 20 Figure 1.

Referring to the drawings in detail, it will be observed that the present timing device comprises a cylinder 10 which is closed at one end by a head 11 and which has slidably therein a piston
 25 12 which is urged constantly toward the head 11 by a spring 13.

In the head 11 and extending transversely thereof is a fuel passageway 14 which, at one end, is provided with a nipple or other suitable fitting
 30 15 for connection with a fuel supply line and which, at its other end, is in communication with a valve chamber 16 in said head.

A bore 17 in the head 11 provides communication between the fuel passageway 14 and the cylinder space *a* between said head 11 and the piston 12 under the control of a check valve 18 which opens toward said cylinder space *a* and closes toward said fuel passageway. Thus, upon movement of the piston 12 in the cylinder 10 away from the head 11, fuel will be drawn into the cylinder space *a* through the bore 17, but will not escape from said cylinder space through said bore upon movement of said piston toward said head 11.

The valve 18 may appropriately be a ball, and a spring 19 preferably is provided to maintain it closed except when the piston 12 is moved away from the head 11.

The piston 12 is intended to be moved manually away from the head 11 and to that end is provided with a suitable handle 20 which may appropriately be in the form of a rod disposed in axial alignment with said piston and extending therefrom through a guide opening in a closure 21 for the end of the cylinder 10 remote from

the end thereof which is closed by the head 11. In this connection, the spring 13 may appropriately be a helical expansion spring as shown and may be interposed between the piston 12 and the closure 21 so as to perform its function of urging said piston constantly toward the head 11.

In the head 11 is a duct 22 which connects the cylinder space *a* with the fuel passageway 14 and which has associated therewith a suitable valve 23 for varying its effective cross sectional area. As shown, said valve 23 may appropriately be of the needle type and may be threaded in the head 11 so that by rotation thereof its inner, pointed end may be moved into and from the duct 22 to vary the effective cross sectional area of the latter. A suitable handle 24 on said valve 23 exteriorly of the head 11 affords a convenient means for finger engagement to effect desired adjustments of said valve.

The valve chamber 16 extends longitudinally of the head 11 and at its inner end is connected with the cylinder space *a* by a port 25, while at its outer end it is provided with a suitable fitting 26 for connection with a part of the fuel supply line leading to an engine.

In the valve chamber 16 is a valve member 27 of the spool type which, at its inner end, is provided with a valve formation 28 for cooperation with a seat surrounding the port 25 to control flow of fuel through said port, and which, at its outer end, is provided with a second valve formation 29 for cooperation with a seat constituted by the inner end of the fitting 26, or by any other suitable means, to control flow of fuel from the chamber 16 to said fitting 26.

The distance between the valve formations 28 and 29 is slightly less than the distance between the seats with which they cooperate. Consequently, when either of said valve formations is closed, the other is open. In this connection, a suitable spring 30 tends constantly to move the valve member 27 inwardly and hence maintains the valve formation 29 normally closed and the valve formation 28 normally open.

Extending from the inner end of the valve member 27 through the port 25 into the cylinder space *a* is a stem 31 which is engageable by the piston 12 just prior to said piston reaching its limit of movement toward the head 11, so that by the final small amount of movement of said piston toward said head 11, the valve member 27 is moved positively outward and thereby the valve formation 28 is opened and the valve formation 29 is closed. In this connection, the effective cross sectional area of the port 25 and the strength of the spring 30 are such, in relation to the strength of the spring 13, that the valve member 26 is not moved outwardly by the pressure generated in the cylindrical chamber *a* by said spring 13, but only by positive action of the piston 12 against the stem 31.

Suitable means, such as a laterally flexible spring arm 32 suitably fastened to the closure 21 and engageable in an annular channel 33 in the handle rod 20, is provided to releasably hold the piston 12 in a starting position spaced any suitable distance from the head 11.

Assuming that the timer is interposed in an engine fuel supply line; that the cylinder space *a* is devoid of fuel, and that the piston 12 is at its limit of movement toward the head 11, it is apparent that by exerting a pulling force on the handle rod 20 the piston will be moved away from the head 11 and thereby fuel will be drawn freely into the cylinder space *a* through the bore

17 from the fuel line constituted in part by the passageway means afforded by the passageway 14, the valve chamber 16 and the fitting 26. It will further be apparent that by pulling on the handle rod 20 until the channel 33 becomes aligned with the spring arm 32 and the latter engages in said channel, a definite starting position of the piston 12 will be established and a definite amount of fuel will be contained in the cylinder space *a*.

Once the cylinder space *a* has been charged with fuel in the manner stated and the piston 12 is in its starting position, the spring arm 32 will act, by engagement with the channel 33, to maintain that condition indefinitely or, in other words, until the spring arm 32 is flexed from said channel 33 by finger pressure exerted against said arm. Thus the engine may be operated as long as desired prior to initiation of a predetermined time period of operation thereof by manual release of the spring arm 32, since the normally open valve formation 29 will permit free flow of fuel from the source of supply to the engine.

Upon release of the spring arm 32, the spring 13 will act to urge the piston 12 toward the head 11 and to force the fuel contained in the cylinder space *a* from said cylinder space. Since the check valve 18 will prevent flow from the cylinder space *a* through the bore 17, and the normally closed valve formation 28 of the valve member 27 will prevent flow of fuel from said cylinder space *a* into the valve chamber 16, the duct 22 obviously constitutes the only avenue for escape of fuel from said cylinder space *a*. The rate at which fuel may escape from the cylinder space *a* through the duct 22 determines the rate of movement of the piston 12 toward the head 11 by the spring 13 and hence determines the amount of time required for said piston to move from its starting position to its position in which it contacts the stem 31 and opens the valve formation 28. The valve 23 constitutes an adjustable means for varying the effective cross sectional area of the duct 22 and hence the rate of escape of fuel therethrough from the cylinder space *a*. Accordingly, by adjusting said valve 23, the time required for the piston 12 to move from its starting position to its position in which it engages the stem 31 and opens the valve formation 28 may be variably predetermined.

When the piston 12 engages the stem 31 and opens the valve formation 28, fuel may escape freely from the cylinder space *a* through the port 25 and hence the final portion of the movement of the piston 12 toward the head 11 is quite quick. When the valve formation 28 is opened the valve formation 29 is simultaneously closed, thereby cutting off the fuel supply to the engine and causing the same to stop. Obviously, the valve formation 29 will be maintained closed until the piston 12 again is manually moved outwardly relative to the head 11, whereupon the spring 30 will act to shift the valve member 27 to close the valve formation 28 and open the valve formation 29.

If desired, but not necessarily, a check valve 34 may be included in the outlet portion of the fuel line between the valve chamber 16 and the engine to prevent fuel from being withdrawn from this portion of the fuel line when the piston 12 is moved outwardly relative to the head to charge the cylinder space *a* with fuel. Appropriately, said check valve 34 may be incorporated in the fitting 26, as shown.

Obviously, the present timing device may advantageously be of very small size and light weight and possesses the further advantage that it utilizes the fuel which it controls as the liquid medium for its hydraulic operation. It is, moreover, smooth and positive in operation and in itself constitutes a fuel reservoir so that the fuel tank may, if desired, be correspondingly reduced in size. It furthermore acts, by subjecting the fuel in the fuel line to pressure, to insure supply of fuel to the engine.

From the foregoing description considered in connection with the accompanying drawings, it is believed that the construction and operation of the present timing device will be clearly understood and its advantages appreciated. It is desired to point out, however, that while only a single, specific structural embodiment of the invention has been illustrated and described, the same is readily capable of specifically different structural embodiments within its spirit and scope as defined in the appended claims.

I claim:

1. A timing device comprising a cylinder, a head closing one end of said cylinder and having therein passageway means constituting part of a liquid supply line, a piston in said cylinder movable toward and away from said head, means for the free flow of liquid from said passageway means into said cylinder between said head and said piston when said piston is moved away from said head, spring means to move said piston toward said head, releasable means to hold said piston in a definite starting position spaced from said head, means providing two outlets for liquid from said cylinder to said passageway means, a spring biased valve maintaining one of said outlets closed against pressure generated in said cylinder by movement of said piston toward said head by said spring means, a valve adjustable to vary the effective cross sectional area of the other of said outlets to regulate the rate of flow of liquid from said cylinder to said passageway means and thereby vary the time required for movement of said piston from its starting position a predetermined distance toward said head, means whereby said piston acts positively to open said spring-biased valve following a predetermined amount of movement of said piston toward said head thus to permit free flow of liquid from said cylinder to said passageway means and consequent quick movement of said piston during the final part of its movement toward said head, and other valve means operable by said piston during the final quick portion of its movement toward said head to close said passageway means against flow of liquid therethrough.

2. A timing device comprising a cylinder, a head closing one end of said cylinder and having therein passageway means constituting part of a liquid supply line, a piston in said cylinder movable toward and away from said head, means for the free flow of liquid from said passageway means into said cylinder between said head and said piston when said piston is moved away from said head, spring means to move said piston toward said head, releasable means to hold said piston in a definite starting position spaced from said head, means providing two outlets for liquid from said cylinder to said passageway means, a spring biased valve maintaining one of said outlets closed against pressure generated in said cylinder by movement of said piston toward said head by said spring means, a valve adjustable to vary the effective cross sectional area of the

other of said outlets to regulate the rate of flow of liquid from said cylinder to said passageway means and thereby vary the time required for movement of said piston from its starting position a predetermined distance toward said head, means whereby said piston acts positively to open said spring-biased valve following a predetermined amount of movement of said piston toward said head thus to permit free flow of liquid from said cylinder to said passageway means and consequent quick movement of said piston during the final part of its movement toward said head, and a normally open valve fixed with respect to said spring-biased valve and movable with the latter during opening thereof to close said passageway means against flow of liquid therethrough.

3. A timing device comprising a cylinder, a head closing one end of said cylinder and having therein a liquid passageway and a valve chamber with which said passageway is connected, a piston in said cylinder movable toward and away from said head, spring means to move said piston toward said head, a check valve-controlled bore permitting free flow of liquid from said passageway to the cylinder space between said head and said piston and denying flow of liquid from said space to said passageway, releasable means to hold said piston in a definite starting position spaced from said head, a duct for flow of liquid from said cylinder space to said passageway, an adjustable valve to vary the rate of flow of liquid from said cylinder space through said duct to said passageway, said valve chamber being in communication with said cylinder space, said head having a liquid outlet communicating with said valve chamber and through the latter with said liquid passageway, a valve member in said valve chamber having two valve formations one controlling flow of liquid between said cylinder space and said valve chamber and the other controlling flow of liquid through said outlet, spring means effective to hold said first mentioned valve formation normally closed against the pressure generated in said cylinder space by movement of said piston toward said head by said first mentioned spring means and to hold said second mentioned valve formation normally open, and means whereby said piston acts positively during the final portion of its movement toward said head to shift said valve member to open said first mentioned valve formation and to close said second mentioned valve formation.

4. A timing device as set forth in claim 1, in which the passageway means includes an outlet portion to one side of the last mentioned valve means, having therein a check valve to prevent flow of liquid therethrough toward said second mentioned valve means.

5. A timing device designed to perform its timing function by cutting off flow of fluid through a conduit after the elapse of a predetermined period of time, said device including a fluid conduit and a chamber, means providing for free flow of fluid from said conduit to said chamber and for throttled flow of fluid from said chamber to said conduit, a member movable outwardly in said chamber to increase its effective size and thus draw fluid into the same from said conduit, means operable in response to a predetermined amount of movement of said member into said chamber to provide for free flow of fluid from said chamber to said conduit and thus provide for quick movement thereafter of said member into said chamber, and means operable in response to said quick

movement of said member to cut off flow of fluid through said conduit.

6. A timing device to cut off the fuel supply to an engine and thus automatically stop the engine after the elapse of a predetermined period of time, said device including a chamber and means for connecting the same with an engine fuel supply conduit for free flow of fuel to the same from the conduit and for throttled flow of fuel from the same to the conduit, a member movable outwardly in said chamber to increase its effective size and thus draw fuel into the same from said conduit, spring means for moving said member into said chamber to expel fuel therefrom into said conduit, a valve for controlling flow of fuel through the conduit, said valve being normally open, means operable in response to a predetermined amount of movement of said

member into said chamber to provide for free flow of fuel from said chamber to said conduit and thus provide for quick movement thereafter of said member into said chamber, and means operable in response to said quick movement of said member to close said valve and thus cut off flow of fuel through said conduit.
